UNITED STATES PATENT OFFICE

PERCY ROBERT DOBSON, OF CALGARY, ALBERTA, CANADA

DOOR-OPERATING MECHANISM

Application filed February 29, 1928. Serial No. 253,048.

This invention relates to improvements in door operating mechanism and the objects of the invention are to provide a simply constructed durable means for opening and closing doors associated with garages, barns and the like whereby such doors when opened or shut are automatically retained in this position and the mechanism adapted to be locked.

Further objects are to provide an improved door operating mechanism that can be manufactured and fitted in quantities at comparatively low cost and which will more efficiently perform the functions required of it.

With the foregoing and other objects hereinafter more fully referred to, the novel features of the invention reside in pivotally mounted door operating arms so arranged and designed that they swing to automatically lock in overlapping position at a predetermined point in their travel to close the door and on being operated straighten out to open the door and to automatically lock in straightened out position at a predetermined point in their travel, and mechanism carried by the door and operable at a point removed therefrom for operating the arms.

Referring now to the drawings in which like characters of reference indicate corresponding parts in each figure,

30 Figure 1 is a sectional plan view of the improved mechanism as applied to a garage door in open position,

Figure 2 is a similar view with the door closed,

35 Figure 3 is a side elevation of the inside of a garage door showing the connecting link for the operating rod,

Figure 4 is a side elevation of Figure 3,

40 Figure 5 is an enlarged fragmentary view of the operating door rods,

Figure 6 is a perspective view of the adjustable control rod connection,

Figure 7 is a vertical section through Figure 6,

45 Figure 8 is a top plan view of Figure 6,

Figure 9 is a side elevation in folded position,

Figure 10 is a plan view of the rack and quadrant,

50 Figure 11 is a side elevation of Figure 10.

Referring now more particularly to the drawings in which an example of my invention is disclosed as applied to a garage door, A designates the garage of any well known construction the door of which is formed in two sections 10 and 11, also of well known construction swingingly mounted on the door jambs.

Above the door opening and substantially midway thereof is rigidly mounted a supporting bracket 13 protruding outwardly and, as here shown, of substantially V-shaped formation but which can be constructed in any suitable form. This bracket 13 is formed at its outer end with a socket or sleeve 14 designed to pivotally engage with the bolt portion 9 of a two-way socket member 15 and to be retained in pivotal engagement therewith by means of a nut 16 and the screw-threaded end 17 of the member 15. The sockets 18 and 19 in the member 15 are arranged one above the other and at substantially right angles to one another and are designed to detachably engage with arms 20 and 21 in turn adjustably connected by means of adjusting screws 22 and 23 to the sleeve members 24 and 25, these sleeve members being formed with extensions 26 adapted to pivotally engage with extensions 27 on the sleeve members 28 and 29 in which are adjustably mounted the arms 30 and 31.

It may here be mentioned that the arms 30 and 31 are preferably, as shown, of greater length than the arms 20 and 21 depending on the width of the door.

Associated with the outer end of the arm 31 and co-ordinating therewith is a bracket member 32 mounted on the inside of the door section 11 and having therein a pivotally mounted socket member 33 designed to engage with the outer end of the arm 31. Associated with the outer end of the arm 30 and rigidly secured on the inside of the door section 10 is a protruding bracket 34 in which is pivotally mounted at 35 a toothed quadrant member 36 the stem of which is socket formed as at 37 to engage with said outer end of the arm 30 while associated and co-ordinating with the pivotally mounted quadrant member 36 is a rack 38 pivotally connected at one end as

at 39 to a bell crank lever 40 pivotally mounted at 41 on the inside of the door section 10.

It will be seen and understood from the foregoing that on this lever 40 being operated the quadrant member 36 is caused to move and with it the arm 30 and the co-ordinating arm 31. For instance, on the mechanism being in the position as disclosed in Figure 1 when the door sections are wide open, and a pull being exerted on the member 40 or pressure downwardly the arms 30 and 31 and 20 and 21 will automatically swing sufficiently far to cause the arms 31 and 30 to move beyond the point of centre of their connection with the arms 20 and 21, thus providing that on pressure being exerted on either of the door sections they will automatically return to closed position.

In carrying out this operation it will also be noted that the arms will automatically assume the position shown in Figure 2 crossing one another while their travel in assuming this position is limited by engagement with the member 14 in which an offset portion or stop 42 is provided. For conveniently operating the lever 40 and through it the mechanism as above described I provide a rod 43 connected at 44 to said mechanism and at its other end adjustably connected at 45 to an operating handle 46 adapted to be locked either from the inside or the outside of the door by a lock of any well known construction (not shown).

From the foregoing the operation of the mechanism will be practically self-evident. Once in position and assuming the doors to be closed, to open them it is only necessary to first unlock and operate the handle 46 when the device will expand from the position as shown in Figure 2 to the open position as shown in Figure 1 carrying with it automatically and simultaneously the door sections 10 and 11 to open them and retain them to all intents and purposes in this position. These arms 30 and 31 on assuming a straight position engage with and are limited in their forward travel by stops 47 and 48 integral with the socket members 24 and 25.

To close the doors the operation has already been described and is accomplished by again operating the handle 46 to in turn operate the lever 40 and throwing the arms 30 and 31 off locking centre.

The bolt portion 9 of the member 15 can be utilized as a medium for power operating the device.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:—

1. Door operating mechanism comprising in combination a door formed in sections, a supporting bracket, jointed arms pivotally connected to the bracket and operatively connected to the door sections, socket members pivotally connected to the bracket protruding at substantially right angles to one another and offset to overlap one another whereby, on the arm sections being swung, said arm sections are retained in crossed closed position.

2. The invention according to claim 1 in which the jointed arms comprise sections connected to one another by means of sleeves in turn pivotally connected to one another, and adjusting screws for said sleeves.

3. The invention according to claim 1 in which a socket member is provided on one of the door sections and adjustably connected to one end, a pivotally mounted toothed quadrant on the other end, a co-operating rack on the other door section, a bell crank lever connected to the rack, an operating handle, a rod connecting the operating handle with the bell crank lever whereby, on the handle being operated, the lever is operated to cause the arms to swing to overlapping or closed position to close the door and, on the handle being further operated, the lever will cause the arms to straighten out to open and retain the door sections in open position.

4. In a device of the character described the combination with a door formed in sections having a socket member on one section and a lever operated rack on the other section, of a branched swingingly mounted socket member common to both sections, sectionally adjustable interlocking arms engaging with the socket member, one of said arms being pivotally connected to the socket-carrying door section and the other of said arms being pivotally connected to a quadrant adapted to co-operate with the rack on the other door section.

In witness whereof I have hereunto set my hand.

PERCY ROBERT DOBSON.
